CLAIM

The ornamental design for a gaming machine cabinet door, as shown and described.

DESCRIPTION

FIG. 1 is a perspective view of the gaming machine cabinet door showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the opposite side being a mirror image.
